ROTARY ABRADING TOOL

Elisha W. Hall, Scituate, Mass.

JUL 17 1951

Application March 6, 1946, Serial No. 652,263

RE 23391

7 Claims. (Cl. 51—193)

1

This invention relates to rotary abrading tools of the class in which the abrading material (either a continuous ring or a plurality of distinct abrading elements) is mounted on a hub which is constructed and arranged to permit removal of the abrading material when too greatly worn for further use, and replacement by other abrading material. The invention is more particularly concerned with a novel and improved construction ensuring safe confinement and retention of the abrading material when in use, while permitting rapid and convenient disassembly when the abrading material is to be replaced. The invention is also concerned with a novel relative arrangement of the abrading material and the hub to give to the latter a conformation which will produce an axial wiping action to minimize grooving of the work. These and other features will appear during the course of the following description when taken in connection with certain embodiments of the invention, while its scope will be pointed out more particularly in the appended claims.

In the drawings:

Fig. 1 is an elevation of a rotary abrading wheel embodying the invention;

Fig. 2 is a sectional view on an enlarged scale on line 2—2 of Fig. 1;

Fig. 3 is a sectional view similar to Fig. 2, showing a modification;

Fig. 4 is a sectional view on line 4—4 of Fig. 1;

Fig. 5 is a modification of the arrangement shown in Fig. 4;

Fig. 6 is an elevation of one of the abrading elements removed from the hub and unfolded to display its form;

Fig. 7 is an edgewise view illustrating one manner of building up the required thickness of abrading material from a strip of cloth of indefinite length;

Fig. 8 is an elevation of a modified abrading element; and

Fig. 9 is a sectional view on line 9—9 of Fig. 8.

Referring to the drawings and to the embodiments of the invention illustrated therein as examples, and having reference at first to Fig. 2, there is shown a rotary abrading wheel comprising a hub 10, and a mass of abrading material 12, attached to the hub in a novel manner presently to be described. In the present example, this mass of abrading material, instead of being in the nature of a continuous ring which it might well be, is in the nature of an annular series of distinct bodies or elements 14, separately attached to the hub.

While the abrading material might be a single thickness of textile material of considerable thickness, and there are such materials available commercially, in the present example it is convenient to employ bias-cut, cotton cloth in the form of a strip 16 of indefinite length built up

to the required thickness as by being first wound in a drum and then flattened (see Fig. 7) to provide a considerable number of plies (sixteen, for example) with folds 18 at each end of the multi-ply mass. This mass may be shaped as desired, and in the present example its corners are angularly chamfered as at 20, and notched as at 22, and perforated as at 24 to reduce the bulk at these points.

10 To prepare these multi-ply abrading elements 14 for attachment to the hub 10, each is provided with a plurality of slots 26, for example two pairs of such slots, preferably reinforced as by patches 28, also slotted in like manner and stitched in place. These patches or reinforcements may be, for example, relatively heavy, strong material such as canvas or duck which imparts great strength to the abrading material at its points of attachment to the hub 10. It is desirable, 15 though not necessary, to unite the cloth plies (see Fig. 6) with rows of stitches 29 which in this example are in lines which (see Fig. 1) are disposed radially. These stitches prevent separation of the plies and lend firmness to the abrading element.

To prepare the described abrading element for attachment to a hub such as the one presently to be described, according to the embodiment now under consideration, the multi-ply mass is folded along a median line x—x (see Fig. 6) which bisects the notches 22 and the aperture 24 and lies midway between slots 26 of each pair, with the result that the slots of each pair then coincide, the notches 22 become chamfers, and the aperture 30 24 becomes a notch in the now folded mass. According to the modification shown in Fig. 8, instead of employing a fold such as that just described, a narrower strip is employed, wound and flattened as before, but having only two slots 26'. 35

40 In this form there is a reinforcement 28' folded over the adjacent edges of the plies so as to embrace them, and stitched in place as before.

To make the material about the slots compact, and to reduce friction between the fabric and the hub 10, that local area about the slots is next 45 treated with suitable material such as paraffin 38, applied hot, or suitable plastic compound such as urea formaldehyde, a cold setting resin glue which will penetrate the fibers, and when 50 subjected to pressure by squeezing in a press, the material is compacted and reduced in bulk so as to be introduced readily into a small space in the hub 10. The binder also tends to maintain the folded condition of the abrading element.

55 Several such abrading elements may be attached to an appropriate hub such as that now to be described, and one or more, usually several, of these hubs placed coaxially on an arbor. One hub which serves the purpose particularly well 60 comprises two sets of holders such as lugs 32 on plates 34 (see Fig. 2), the lugs on one plate being

staggered, i. e., alternating with the lugs on the other plate so that when a lug 32 on one plate is introduced through one pair of slots 26 and the next lug 32 on the other plate is introduced through the other pair of slots 26, a peculiar and desirable formation of the abrading element results. One such formation is illustrated in Fig. 4 and is characterized by a reverse curve or S curve, while another formation is illustrated in Fig. 5, and is characterized by a U curve. Each formation has advantages when in use, particularly a wiping action in an axial direction, tending to minimize grooving of the work. Each of these formations is possible by the use of the staggered arrangement of the lugs. To maintain this staggered arrangement, the plates 34 are suitably secured together for relative non-rotation, as, for example, by securing them by screws 36 to a central disk 38 which may be wood, laminated or otherwise.

In the present embodiment, the lugs 32 of one plate 34 have their free ends extending in an opposite direction to the lugs of the other plate. It is preferred not to rely upon the lugs 32 alone to prevent accidental detachment of the abrading elements from the hub, even though the staggered arrangement and the folds of the abrading elements tend to prevent such detachment. Instead of relying wholly upon these arrangements, I prefer to employ means positively to lock the abrading elements in place on the lugs. One such means will now be described, reference being had to Fig. 2. This particular retaining means involves simply associating with each plate 34 another plate 40 having a marginal portion 42 which overlies the several abrading elements. When several assemblies such as the one shown in Fig. 2 are placed coaxially on an arbor and secured thereon by the usual clamping plates and nut threaded upon the arbor, the retaining plates prevent accidental disengagement of the abrading elements from the lugs. However, before the assembly is placed upon the arbor, it may be desirable to hold the assembly together, temporarily, as by a bolt 44 having a nut 46.

The retaining plate 40 may take the form shown in Fig. 2 with a circumferential flange or lip 48 and with an offset 50 which constitutes a spacer preventing the margin 42 from unduly restraining the abrading elements 14, or it may take the form shown in Fig. 3 in which there is a plate 40A which has no offset but instead the plate 34A has an offset 50A which constitutes a spacer. Some sort of spacer is desirable though perhaps not necessary, as without the spacer the retaining plate would then be unrestrained and would clamp the abrading elements firmly to the plates having the lugs.

Having thus described these embodiments of the invention, what I claim is:

1. In a rotary abrading tool, the combination of a hub having two sets of lugs, the lugs of one set alternating with the lugs of the other set, and the lugs of one set having free ends extending in a direction opposite to those of the other set, and a circumferential mass of abrading material having alternate openings receiving alternate lugs.

2. In a rotary abrading tool, the combination of two circumferential sets of holders, the holders of one set alternating with and being displaced axially with relation to the holders of the other set, each set having free ends extending in a direction opposite to those of the other set, and abrading material held by the holders of both

sets and extending lengthwise of the axis from one set to the other.

3. In a rotary abrading tool, the combination of two circumferential sets of holders, the holders of one set being displaced axially with relation to and alternating with the holders of the other set, each set having free ends extending in a direction opposite to those of the other set, and a circumferential set of abrading elements, each held in part by a holder of one set, extending lengthwise of the axis of rotation, and each being held in part by the next succeeding holder of the other set.

4. In a rotary abrading tool, the combination of two circumferential sets of holders, the holders of one set being displaced axially with relation to and alternating with the holders of the other set, and a circumferential set of abrading elements, each held in part by a holder of one set having a curved offset formation extending lengthwise of the axis of rotation, and each being held in part by the next succeeding holder of the other set.

5. In a rotary abrading tool, the combination of two circumferential sets of holders, the holders of one set being displaced axially with relation to the holders of the other set, and a circumferential set of abrading elements each held in part by the holders of one set and in part by the holders of the other set, and each having an intermediate offset portion displaced lengthwise of the axis.

6. In a rotary abrading tool, the combination of two circumferential sets of holders, the holders of one set having free ends extending in a direction opposite to those of the second set and displaced axially with relation to and staggered with relation to the holders of the second set, and a set of abrading elements each having two openings, one opening receiving a lug of one set and the other opening receiving a lug of the other set, and each abrading element having a portion offset intermediate its openings and displaced lengthwise of the axis.

7. In a rotary abrading tool, the combination of a hub having two sets of lugs extending lengthwise of the axis of rotation, the lugs of one set being displaced axially with relation to and staggered with relation to the holders of the second set, one set having free ends extending in the opposite direction to those of the other set, and a set of abrading elements, each having two openings, one receiving a lug of one set and extending thence lengthwise of the axis of rotation to and receiving a lug of the other set.
